UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

METHOD OF MINING AND MINING APPARATUS.

Application filed July 1, 1921. Serial No. 481,844.

My invention relates to a method of mining, particularly adapted for dislodging coal from a mine vein by means of continuous forwardly applied splitting actions at 5 spaced-apart points between the floor and roof of the mine chamber. My invention also relates to apparatus for carrying out such method of mining, comprising splitting tools arranged in spaced-apart relation and 10 having powerful continuous forward movements effected thereby.

One of the objects of my invention is the provision of apparatus for efficiently carrying out the method referred to; a further 15 object of the invention is the provision of apparatus for mounting spaced apart splitting tools between the floor and roof of the mine chamber for continuous forward operation for each predetermined position of the 20 mining machine.

Another object of the invention is the provision of a plurality of spaced-apart splitting tools on an adjustable supporting frame adapted to be anchored between the floor 25 and roof of the mining chamber so that such splitting tools may be operated with continuous forward movements for each anchored position of such frame.

Another object of the invention is the provision 30 of a mining machine comprising spaced-apart splitting tools adapted to be operated by continuous forward movements and mechanism for adjusting the position of the mining machine and anchoring the same 35 in adjusted position.

A further object of the invention is the provision of splitting tools having a central forwardly projecting claw in advance of a plurality of spaced-apart claws spread out 40 in fan formation to engage the coal on both sides of the advanced claw to dislodge the coal on both sides of the coal preliminarily split away by the central claw.

Other objects of the invention will appear 45 hereinafter, the novel features and combinations being set forth in the appended claims.

Referring to the accompanying drawings,

Figure 1 is a plan view of my improved mining machine showing the narrow elongated dimension thereof in position to move longitudinally in a long wall operation;

Fig. 2 is an elevational view of the mining machine shown in plan in Fig. 1;

Fig. 3 is a sectional plan view taken on 55 the line 3-3 of Fig. 2;

Fig. 4 is a sectional elevation taken on the line 4-4 of Fig. 2, looking rearwardly in the direction of the arrows;

Fig. 5 is a sectional elevation taken on the line 5-5 of Fig. 2, looking in the direction 60 of the arrows;

Fig. 6 is a sectional elevation taken on the line 6-6 of Fig. 2, looking rearwardly in the direction of the arrows;

Fig. 7 is a sectional plan view taken on 65 the line 7-7 of Fig. 2;

Fig. 8 is a perspective view of the claw-like splitting tool particularly adapted to be located at or near the roof or floor; and

Fig. 9 is a perspective view of a modified 70 claw-like splitting tool particularly adapted to be located intermediate the floor and roof.

Referring to Fig. 2, it will be seen that the supporting frame or base frame 10 is provided with a serrated bottom 11, to act 75 as the lower shoe of a floor and roof jack, the upper shoe being shown at 12, which is provided with an upper serrated surface 13. The shoes 10 and 12 are preferably rectangular in shape to provide a mining machine 80 which will be comparatively narrow in width, as shown in Fig. 1.

Rigidly connected to the supporting frame 10 and extending upwardly therefrom is a cylinder 14 for receiving the plunger 85 15 extending downwardly from the shoe 12, as shown in Fig. 4. Rigidly connected to the upper end of the plunger 15 and extending forwardly therefrom is a horizontal cylinder 16 for receiving the horizontal plunger 90 17 having the splitting tool 18 mounted on the outer end thereof.

In a similar manner, a horizontal cylinder 19 extends forwardly from the upper end portion of the cylinder 14, and likewise a 95 horizontal cylinder 20 extends forwardly from the base frame 10 and from the lower end of the cylinder 14. It should be noted that the cylinders 19 and 20 are rigidly connected to the base frame 10 and to the cylinder 14, whereas the cylinder 16 and the plunger 15 are movable up and down, together with the shoe 12 relatively to the cylinder 14 and the base 10. The uppermost splitting tool 18 may therefore be adjustable 105 in elevation, and in Fig. 4, I have shown a manually operated valve 21 for controlling the supply of fluid pressure from the supply pipe 22 through the pipe 23 to the cylinder 14 beneath the plunger 15. The fluid pres- 110

sure medium may be controlled by the valve 21 for effecting the lifting of the plunger 15, together with the parts carried thereby, or the lowering of the latter by the weight of 5 said plunger and said parts when the valve 21 is opened to exhaust.

In order to maintain the cylinder 16 in vertical alinement with the cylinders 19 and 20, the upwardly extending guideway 24 10 from the cylinder 14 may be provided with inner flat surfaces, against which fit the corresponding flat surfaces of the rear end of the upper supplemental frame on which the shoe 12 is mounted. The guideway 24 and 15 the irregular surfaces 25, thereby act as a splined guideway for preventing the cylinder 16 from turning horizontally relatively to the base frame 10.

The cylinders 16, 19 and 20 are respectively provided with elongated tubular guides 26, 27 and 28, for the plungers 17, 29 and 30. To the uppermost plunger 17 is keyed at 31 the claw-like splitting tool 18, shown in perspective in Fig. 8. A similar 25 splitting tool 32 is keyed at 33 to the lowermost plunger 30. To the intermediate plunger 29 is keyed at 34 the splitting tool 35 shown in perspective in Fig. 9.

The claw-like splitting tool 18, shown in 30 Fig. 8, is provided with a central claw 36 advanced beyond the series of lateral claws 37 and 38, so that the central claw may initiate the splitting of the material by a concentration of the dislodging force at 35 substantially a single point.

By referring to Figs. 8 and 9 it will be seen that the claw-like splitting tools are in reality in the shape of hands each having 40 spaced penetrating wedging fingers and a deflecting palm. Each splitting tool also is provided with a wrist by means of which the dislodging tool may be detachably keyed to the outer end of the operating plunger in a predetermined position. In Fig. 2 the 45 dislodging hands are keyed at 31, 34 and 33 to the outer ends of the plunger rods 17, 29 and 30, respectively. By referring to Fig. 3 it will be seen that the splined connection at 44 prevents the plunger rod from 50 turning relatively to the guide 26 and the cylinder 16. By reason of the hand-shaped dislodging tool being keyed to the outer end of the plunger rod such dislodging tool is prevented from turning relatively to the 55 rod. Therefore when the dislodging tools are operated rectilinearly the deflecting palms remain in the desired positions to assist the wedging tools in forcing the split coal away from the unmoved mass.

60 Thereafter, on account of the previous loosening of the material by the advanced splitting member 36, the operation of the lateral series of claws 37 and 38 to dislodge the material will be greatly facilitated. However, it is preferred to arrange the

series 37 at right angles approximately to the series 38, so that the advanced member 36 may act in the corner, at the roof or floor, and the lateral series 37 and 38 scrape along the roof or floor and the sidewall, to 70 dislodge the material therefrom and to properly trim the surfaces as desired. For instance in the arrangement shown in Figs. 1 and 2, the splitting member 36 is in position to engage the uppermost corner at 75 39 of the mine wall 40, from which the coal is being dislodged. The upper horizontal series of splitting tools 38 will then dislodge the material from the roof at the desired elevation and the vertical series of claws 80 37 will dislodge the material along the mine wall below the advanced splitting tool 36.

The lowermost claw-like splitting tool 32 is also provided with an advanced splitting member 36', a vertical series of claws 37' 85 for dislodging the material from the upright surface of the wall, and a horizontal series of claws 38' to properly trim the floor.

The intermediate claw-like splitting tool 90 35 is provided with an advanced splitting member 41 and upper and lower splitting members 42 and 43 arranged in vertical series. In this arrangement the pressure 95 may be concentrated on the intermediate advanced member 41 to initially split away some of the material and thereby facilitate the subsequent action of the lateral splitting members 42 and 43. Preferably, the rear splitting members 42 and 43 are in 100 vertical alinement with the claw series 37 and 37', when the splitting tools are all in their initial positions as shown at 18, 35 and 32, in Fig. 2.

Each of the splitting tools, 18, 35 and 32 105 is operable independently of the others, and each is preferably arranged to move rectilinearly and prevented from being turned on the axis of the plunger with which it is connected, or on the axis of the cylinder in 110 which said plunger moves. While Fig. 3 is a sectional plan view, taken on the line 3-3 of Fig. 2, it should be understood that Fig. 3 also represents the construction for operating the splitting tools 35 and 32. As 115 shown in Fig. 3, the plunger 17 is splined at 44, to the plunger guide 26, so that the plunger 17 cannot rotate relatively to the cylinder 16, and therefore since the splitting tool 18 is keyed at 31, to the outer end of the plunger 17, such splitting tool is confined to 120 rectilinear movements at all times. The arrangement is the same with respect to the plungers 29 and 30, being splined to the tubular guides 27 and 28, respectively, so 125 that the splitting tools 35 and 32 will be confined to rectilinear feeding movements, these splitting tools being keyed at 34 and 33, respectively, to the outer ends of the plungers 29 and 30.

Referring to Figs. 3 and 5, it will be seen that each of the cylinders 16, 19 and 20 is provided with pipes 45 and 46 leading to the ends of the cylinders. As shown in Fig. 3, 5 a valve 47 controls the supply of fluid pressure from the pressure line 48, to the piston 79, to effect advance or retraction of the splitting tool. Inasmuch as the action of the splitting tools must be a powerful continuous 10 forward movement, I prefer to employ an incompressible liquid as a pressure medium, and hydraulic motors are therefore desirable for operating the splitting tools. In a manner similar to that shown in Fig. 3, 15 the liquid pressure motors 19 and 20 may be respectively controlled by means of the manually operated valves 49 and 50 shown in Fig. 5. The pressure line is indicated at 80, 51 and 52, and the respective exhaust 20 ports are indicated at 53, 54 and 55. It will thus be seen that the operator may effect the advance or retraction of each splitting tool 18, 35 and 32, individually, and each independently of the other.

25 On account of the individual operation of the splitting tools, my improved method may be carried out by first operating the valve 49 and effecting the advance of the intermediate splitting tool 35, so as to dislodge 30 the coal along the space intermediate the floor and roof. Then the uppermost splitting tool should be advanced, and on account of the previous space provided by the intermediate splitting tool, the coal from 35 above or near the roof may be expanded downwardly as well as laterally and outwardly, thus facilitating the dislodgement of the coal above by first providing such intermediate space with the intermediate 40 splitting tool. Finally, the lowermost splitting tool may be advanced, and on account of the coal above having been already dislodged the coal at and near the floor may expand upwardly as well as forwardly and laterally, during the operation of such 45 lowermost splitting tool 32. It will thus be seen that by first providing for dislodgement of the coal intermediate the floor and roof, ample space is provided for the spreading 50 of the coal downwardly as well as laterally when the uppermost splitting tool acts, and in a similar manner after the coal has been dislodged from above, the material acted on by the lowermost splitting tool will have 55 ample space into which to spread upwardly as well as laterally.

When the valve 21 is opened to exhaust, the plunger 15 will descend and release the shoe 12 from the roof. In order to move 60 the mining machine to a new location, I have provided a hydraulic motor 56, pivotally mounted at 61 at its forward end, to the brackets 58 and 59, extending rearwardly from the base frame 10. The bracket 58 is 65 provided with a series of openings 60 ar-

ranged along an arc with the pivot 61 as a center. The pin 62 is adapted to be inserted through one of the openings 60 into a recess at 57 on the upper side of a cylinder 56 intermediate the ends of the latter. It will 70 thus be seen that the hydraulic motor 56 may be adjusted on the pivot 61 to any desired angular relation relative to the frame 10 and held in such adjusted position by the pin 62. In this manner, the direction of 75 forward travel of the mining machine may be varied from time to time as desired. In Fig. 7 I have illustrated the hydraulic motor 56, with its pivotal connection 61. Extending outwardly from the piston 63 is a 80 plunger 64, the latter being provided at its outer end with a ring or collar 65, through which projects a cylinder 66, as shown in Fig. 6. Movable vertically in the cylinder 66 is a plunger 67. The upper end of the 85 latter is provided with a roof-engaging shoe 68, and the lower end of the cylinder 66 is provided with a floor-engaging shoe 69.

By means of a valve 70, shown in Fig. 7, the motor 56 may be controlled by controlling the flow of fluid pressure from the pipe 71 to the pipes 72 and 73. In similar manner, the motor 66 may be controlled by the valve 74. In the latter, only one pipe 75 leading to the cylinder 66 is necessary, as the plunger 67 may be restored by its own weight when the pressure in the cylinder 66 is relieved. By operating the roof jack 66, 67, shown in Figs. 2 and 6, an anchored abutment is secured for the motor 66 to operate 100 against to move the mining machine forward to a new location. When the shoe 12 is in released position, this operation of the motor 56 against the abutment may take place, and then the roof-jack shown in Fig. 105 4 may again be operated to securely anchor the mining machine in adjusted position. Thereupon, the roof jack shown in Fig. 6 may be released and the motor 56 operated to move the said roof jack forward to a new 110 location.

During the forward movement of the roof jack 66, 67 to a new location, a spring 76 is provided on top of the spring 65 to yieldingly support the plunger 66 by engaging 115 the under side of the collar 77, which is adjustable in elevation on the cylinder 66 and held in adjusted position by the set-screw 78. In this manner the shoe 69 is held up off the floor when the shoe 68 is released and 120 is in its lower position. When the roof jack 66, 67 is again operated, the spring 76 will be compressed so as to secure the necessary spreading apart of the shoes 68 and 69. It is only when the roof jack is released that 125 the spring 76 is free to act to lift the shoe 69 for sufficient clearance to permit free movement over the mine floor to a new position.

Obviously those skilled in the art may 130

make various changes in the details and arrangement of parts without departing from the spirit and scope of my invention, as defined by the claims hereto appended. I wish therefore not to be restricted to the precise construction herein disclosed.

Having thus fully described and shown an embodiment of my invention, what I desire to secure by Letters Patent of the United States is:

1. The long wall method of mining coal which consists in first penetrating the solid coal face in a general horizontal direction along a narrow space at a mine vein and by wedging action splitting large pieces of coal from the vein intermediate the floor and the roof of the mine chamber, and following such dislodgement of the coal by another penetrating and wedging operation in such narrow space to dislodge additional coal in large pieces from the mine vein while spreading into the space afforded by the first dislodgement as well as laterally.

2. The long wall method of mining coal which consists in applying in a narrow space continuous forward concentrated pressure along the face of a mine vein in a general horizontal direction on a splitting tool to dislodge the coal between the floor and roof of the mining chamber to a limited extent and then applying in such narrow space similar dislodging actions along such face above and below the space provided by dislodgement of the limited intermediate portion to dislodge the coal from the upright mine wall near the floor and near the roof.

3. The long wall method of mining coal which consists in first in a narrow space dislodging the coal from an upright face of a mine wall in a general horizontal direction along such face between the floor and roof of the mine chamber then subsequently in such narrow space dislodging the coal from such mine wall along such face immediately below the roof and immediately above the floor while simultaneously trimming the roof and the floor to have approximately horizontal surfaces.

4. In a mining machine, the combination with a supporting frame, of a dislodging tool comprising a pointed wedging splitting member adapted to be inserted in a corner and comprising also a vertical series of dislodging members and a horizontal series of dislodging members associated with said splitting members to follow the same, and means for operating said dislodging tool by moving the same along such corner directly into contact with the material to be dislodged.

5. In a mining machine, the combination with a narrow supporting frame, of a hydraulic ram, and a dislodging tool mounted on said hydraulic ram with a free and unobstructed space in advance thereof and hav-

ing spaced-apart wedging devices in position to engage the mineral in its native bed and split the same therefrom and by wedging action in directions intercepting each other splitting the mineral from the mine vein.

6. In a mining machine, the combination with a supporting frame, of a hydraulic ram, and a right angle dislodging tool comprising wedges facing each other and mounted at the other end of said ram with the space in advance of said tool free and unobstructed and in position to penetrate the mineral in its native bed and dislodge the same from the mine vein.

7. A dislodging tool for mining machines, comprising a series of claws arranged in right-angle relation, with the corner claw extended in advance of the series on both sides thereof.

8. A dislodging tool for mining machines, comprising splitting members arranged in right-angle relation to adapt the dislodging tool for operation along an upright mine wall at the corner adjacent an approximately horizontal surface, with the corner splitting member extending in advance of the horizontal and upright series of splitting members.

9. In a mining machine, the combination with a supporting frame, of a plurality of spaced-apart splitting tools mounted on said supporting frame one above another in an upright series, individual hydraulic motors for the splitting tools, and means for individually controlling said hydraulic motors to secure separate and independent operations of said splitting tools in cooperation to dislodge the material from an upright mine wall.

10. In a mining machine, the combination with a supporting frame, of means for securely anchoring said frame adjacent an upright mine wall between the floor and roof thereof, spaced-apart penetrating wedging tools, and hydraulic motors for operating said tools to cause the same to penetrate the coal in its native bed by a powerful continuous forward movement against said abutment to dislodge the material from the mine vein in continuation of such mine wall.

11. In a mining machine, the combination with a supporting frame adapted to rest on and move over a mine floor, of a hydraulic roof jack for anchoring said frame between the floor and roof of a mine chamber, and multiple splitting tool mechanism comprising a plurality of spaced-apart penetrating wedges and hydraulic motors for individually operating said penetrating wedges to act with a steady forward powerful pressure exerted continuously in predetermined directions during the dislodgment of the mineral from the unmined mass.

12. In a mining machine, the combination

- with a supporting frame, of means for anchoring the same to serve as an abutment, a plurality of penetrating wedging tools, fluid pressure motor mechanism comprising 5 plunger rods for individually supporting the respective tools with the spaces between the tools free and unobstructed as well as the spaces in advance of said tools, and means for operating said fluid pressure motor mechanism by pushing the tools with a continuous forward pressure to cause said tools to penetrate the coal in its native bed to dislodge the same by wedging action.
13. In a mining machine, the combination 15 with a supporting frame, of a hydraulic roof jack for anchoring said frame between the floor and roof of a mine chamber, a plurality of individual dislodging tools each having a penetrating end and wedging surfaces receding therefrom, means for supporting said tools in an upright series in spaced-apart relation with the spaces between the supporting means as well as in advance of said tools entirely free and unobstructed, horizontally 20 extending liquid pressure motor mechanism mounted on said frame and connected to said supporting means, and means for controlling said motor mechanism for securing powerful forward pushing action on said 25 dislodging tools to cause the same to penetrate the solid coal in its native bed with a continuous forward movement to split such coal and dislodge the same over an area extending between the floor and roof of the 30 mine chamber.
14. In a mining machine, the combination 35 with a supporting frame, of means for anchoring the same, a plurality of superposed liquid pressure motors extending horizontally from said frame to constitute a narrow mining machine framework, and a plurality of spaced-apart dislodging tools connected in upright series respectively to said motors to maintain the narrow width 40 of the mining machine and enabling the latter to operate in a narrow space along an upright mine wall.
15. In a mining machine, the combination 45 with a narrow upright frame, of means for anchoring the same between the floor and roof of the mine chamber, a plurality of liquid pressure motors extending forwardly from said frame within the space thereof extending longitudinally to maintain the narrow 50 width of the mining machine, and a plurality of dislodging tools mounted respectively on said motors in upright series for operation along the narrow space in which the mining machine is adapted to 55 travel.
16. In a mining machine, the combination 60 with a supporting frame, of dislodging mechanism mounted thereon, a motor pivotally connected to said frame for swinging adjustment laterally relatively thereto,
- means between said motor and said frame for holding the latter in adjusted angular relation, an abutment for the rear end of said motor, and means for controlling said motor to secure movement of said frame and 70 said dislodging mechanism to a new position.
17. The combination with a mining machine, of a motor pivoted thereto, intermediate means for holding said motor in adjusted angular relation to said mining machine, an abutment for the rear end of said motor, means for anchoring said abutment, and means for controlling said motor against the anchored abutment to secure movement of the mining machine to a new 75 location.
18. The combination with a mining machine, of a liquid pressure motor pivotally connected thereto and extending horizontally rearwardly therefrom, intermediate 80 means for holding the said motor in adjusted angular relation to said mining machine, an additional liquid pressure motor adapted to occupy an upright position between the floor and roof of the mine chamber and connected to the rear end of said first-named motor, roof-jack mechanism operated by said additional motor to serve as an abutment for said first-named motor to act against, and means for controlling said 85 first-named motor to move the mining machine to a new location when said roof jack mechanism is in anchored position.
19. In a mining machine, the combination 90 with a supporting frame, of a fluid pressure motor comprising a reciprocable rod, a guide for said rod splined to the latter to prevent relative rotation thereof, a claw-like dislodging tool comprising spaced-apart 95 penetrating devices having wedging surfaces extending rearwardly therefrom, said tool being adapted to penetrate the solid face of a mine vein and by wedging action split large portions of the mineral from the vein adjacent said spaced-apart penetrating devices, and means for controlling said motor to effect a continuous forward powerful 100 pressure on said clawlike tool to cause said spaced-apart devices to penetrate the mineral in its native bed to split the same over 105 a wide area and by wedging action dislodge such mineral from the unmined mass in large pieces.
20. In a mining machine, the combination 110 with a supporting frame, of a plurality of superposed horizontally extending mining tools each having the space in advance thereof free and unobstructed and each adapted to penetrate the solid coal of an upright mine wall and by wedging action split the coal 115 from the unmined mass over a wide area, means for confining the operating strokes of said tools to rectilinear paths of travel, means for operating said penetrating tools by imparting rectilinear movements thereto 120
- 125
- 130

to effect the dislodgment of coal over a wide area, and means for adjusting the elevation of the uppermost penetrating tool.

21. In a mining machine, the combination 5 with a supporting frame, of a plurality of liquid pressure motors mounted on said frame in spaced-apart relation and for rectilinear operation, dislodging tools mounted on said motors for rectilinear actuation 10 thereby and each comprising penetrating devices provided with wedging surfaces adapted to dislodge the coal from the unmined mass, and means for adjusting the spacing of said motors and the spacing of 15 said dislodging tools.

22. The combination with a supporting frame, a roof jack comprising relatively movable members, a horizontally extending liquid-pressure motor mounted on said supporting frame, a dislodging tool connected to said motor, an additional horizontally extending liquid pressure motor mounted on the movable member adjacent the roof, and an additional dislodging tool connected to 25 said additional motor for operation at an adjusted elevation in accordance with the position of the roof member of said roof jack when the latter is in anchored position.

23. In a mining machine, the combination 30 with an upright supporting frame, of means for anchoring the same to serve as an abutment, a plurality of spaced-apart horizontally extending liquid-pressure motors, a plurality of dislodging tools connected respectively to said motors to act along an upright mine wall at the roof and at the floor and intermediate the roof and floor at concentrated points in spaced-apart relation, and means for controlling said motors to 35 operate said dislodging tools against the anchored abutment to cause such tools to penetrate the mineral and by wedging action rip and tear the same from the unmined mass.

24. In a mining machine, the combination 45 with an upright supporting frame comprising a hydraulic roof jack having an upright plunger connected to the roof-engaging shoe, a plurality of spaced-apart horizontally extending hydraulic motors connected to the 50 lower and intermediate portions of said frame, an additional hydraulic motor connected to said plunger to extend horizontally therefrom adjacent the roof of the mine chamber and movable up and down with 55 said plunger, dislodging tools connected respectively to said motors in an upright series for exerting dislodging actions at spaced-apart concentrated points intermediate the floor and roof of the mine chamber, and 60 means for controlling said motors to operate said dislodging tools.

25. In a mining machine, the combination with a comparatively narrow supporting frame, of a roof jack for anchoring the same and having an upper movable member, a

hydraulic motor extending from said upper member along the roof of the mine chamber, an additional hydraulic motor extending horizontally from said frame along the floor of said mine chamber, an intermediate hydraulic motor extending horizontally from said roof jack, said spaced-apart hydraulic motors being confined to the narrow longitudinal space between the sides of said supporting frame, right-angle dislodging tools 70 connected to the floor and roof motors and each having a forwardly extending piercing member to dig into the corner and right-angle series of dislodging members at the sides of said piercing members in position 75 to trim the floor and the roof and the adjacent walls, means for confining said series of dislodging members to said positions for trimming the floor, roof and walls, and an intermediate dislodging tool comprising a 80 forwardly extending piercing member to receive concentrated pressure from the intermediate motor on the mine vein intermediate and spaced from the floor and roof dislodging tool.

26. In a mining machine, the combination with an upright flat framework comparatively narrow in a direction extending transversely back from the mine wall and adapted to occupy an upright position in a plane extending longitudinally of an upright mine wall, of expansible dislodging mechanism mounted on said frame, means for anchoring said frame, and means for operating said expansible mechanism longitudinally of said frame while the latter is anchored and occupies a narrow space adjacent the wall.

27. In a mining machine, the combination with a frame having front and rear upright faces a comparatively short distance apart, of a plurality of superposed expansible operating devices mounted on said frame to tend therefrom along lines between planes extending through said spaced-apart faces, 105 and dislodging tools connected to said operating devices in position to dislodge the face of a mine vein along a space in alignment with the longitudinal length of said frame.

28. In a mining machine, the combination 115 with a base frame, of a supplemental frame, dislodging mechanism mounted on said supplemental frame and confined thereby for rectilinear movements relatively thereto, means for adjusting the elevation of said supplemental frame relatively to said base frame to adjust the elevation of said dislodging mechanism, and means for preventing arcuate movement of said supplemental frame relatively to said base frame while 120 said dislodging mechanism is confined to rectilinear movements.

29. A dislodging tool for mining machines, comprising a hand having a supporting wrist, a deflecting palm, a penetrating 130

wedging finger projecting from said palm, and shorter trimming fingers projecting from said penetrating wedging finger on both sides thereof.

5 30. A dislodging tool for mining machines, comprising a hand having a supporting wrist, a deflecting palm, a penetrating wedging finger projecting forwardly from said palm, and an upright series of short

10 trimming fingers.

31. A dislodging tool for mining machines, comprising a hand having a supporting wrist, a deflecting palm, and a plurality of spaced-apart penetrating wedging fingers

15 projecting varying distances from said deflecting palm.

32. A dislodging tool for mining machines, comprising a hand having a supporting wrist, a deflecting palm, spaced penetrating wedging fingers projecting from said

palm, and an upright series of trimming fingers.

33. A dislodging tool for mining machines, comprising a hand having penetrating wedging fingers with the inner wedging 25 surfaces facing each other, a deflecting palm merging into said inner wedging surfaces, and a supporting wrist.

34. A dislodging tool for mining machines, comprising a pointed wedging splitting member adapted to be inserted into a corner and comprising also two series of trimming tools associated with said splitting member to follow the same, one series being associated with one side of said member and 35 the other series with the other side thereof.

Signed at Washington, D. C., this 1st day of July, 1921.

EDMUND C. MORGAN.
